UNITED STATES PATENT OFFICE

DONNA E. MINTON AND SENETH H. GALLAGHER, OF PARSONS, KANSAS

BURIAL CRYPT

Application filed March 20, 1929. Serial No. 348,447.

The present invention has reference to improvements in burial structures and more particularly to a novel crypt for receiving and thoroughly protecting caskets.

5 The principal object of the invention is to provide a crypt which will not only exclude all moisture from the exterior, but will also absorb any moisture emanating from the body contained in the casket.

10 Another important object of the invention is to provide a crypt in which the side walls and lid are thoroughly reinforced against rupture.

15 Still another important object is to provide means for firmly securing the lid to the casket container portion of the crypt.

These and other objects of the invention will become more apparent to the reader, after considering the invention as described 20 and claimed hereinafter.

In the drawings:

Figure 1 represents a top plan view of the improved crypt with the lid removed.

25 Figure 2 represents a longitudinal vertical sectional view through the crypt.

Figure 3 is a vertical transverse sectional view through the crypt.

Referring to the drawings, wherein like numerals designate like parts, the invention 30 includes a rectangular box like container 3, preferably of metal or some equally strong, durable and air excluding material.

The metallic container 3 has an external and internal coating of concrete form to 35 protect the metal from corrosion or other deteriorating reaction of metal.

The container 3 is open at its top side and has a bead 5 of substantially U-shaped cross section inverted for disposition at the upper

40 edge portion of the container in the position shown in Figure 2. The cement covering of the container extends over the bead 5 in the manner shown and that portion of the cement at the inner side of the container

45 3 and adjacent the top thereof is partially removed to provide a shoulder 6 for supporting a tray, generally referred to by numeral 7. This tray is of rectangular shape, with its side walls bevelled as designated by numeral 8, the bottom of the tray

7 being provided with a longitudinally extending split 9, from the edge portions of which an upstanding wall 10 extends.

Elevated rests 11 are provided upon the floor of the cement covered container 3, for 55 spaciously supporting a casket therein.

The side walls of the cement covered container 3 has its cement covering formed with a groove 12 extending around its perimeter to receive some of the binding agents placed 60 between the space between the upper edge portion of the container and the bevelled side walls of the tray 7. The binding agent is not shown in the drawings. The lid 13 is of reinforced concrete construction with 65 its edge portion diverged downwardly as at 14, for disposition upon the somewhat bevelled upper edges of the cement cover container 3. The longitudinally and transversely extending reinforcing elements 15 70 have their end portions bent downwardly for disposition between the space between the bevelled side walls of the tray 7 and the upper portion of the cement covered container 3. The hardening of the binding 75 agent placed within this case will firmly secure the lid 13 to the cement covered container 3.

A suitable quality of absorbent material is to be placed within the tray 7 to absorb 80 moisture developed in the manner aforementioned within the crypt.

It is apparent that through the use of the improved crypt, a body may be preserved for a greater period of time than in the 85 conventional crypt through which moisture may penetrate from the exterior and in which no means is generally provided for absorbing the moisture generated within.

Obviously, in the production of this novel 90 structure, certain changes in the specific shape, size and materials may be resorted to, without departing from the spirit or scope of the invention as claimed herein- 95 after.

Having described the invention, what is claimed as new is:

1. A burial crypt comprising a moisture proof container adapted for receiving a casket, a tray for receiving an absorbent ma- 100

aterial supported within the upper portion of the container, said tray being provided with an opening in the bottom thereof and a lid for said container, the side walls of said tray being bevelled to provide a channel between the container and said tray wherein a suitable binding agent may be placed.

2. A burial crypt comprising a moisture proof container adapted for receiving a casket, a tray for receiving an absorbent material supported within the upper portion of the container, and a lid for said container, the side walls of said tray being bevelled to provide a channel between the container and said tray wherein a suitable binding agent may be placed, and a reinforcing element in the said lid, said elements being bent downwardly at their ends for disposition within said channel.

20 In testimony whereof we affix our signatures.

DONNA E. MINTON.
SENETH H. GALLAGHER.
